UNITED STATES PATENT OFFICE

JOHN BRADLEY DEANE, OF BROOKLYN, NEW YORK

RADIO LOUD-SPEAKER

Application filed May 17, 1927. Serial No. 192,108.

My invention relates to improvements in radio loud speakers and the object of the invention is to devise a loud speaker which has an improved clarity of tone and in which the volume of sound therefrom is greater for a given diameter of diaphragm than is at present the case. Conversely where the volume of sound is not to be increased the diameter of the instrument can be reduced.

10 My invention consists of a loud speaker constructed and arranged all as hereinafter more particularly described and illustrated in the accompanying drawing in which:—

Fig. 1 represents a vertical section through one form of device constructed according to my invention.

Fig. 2 is a vertical section thereof through the line 2—2 (Fig. 1).

Fig. 3 is a side elevation (partly in section) of a modified form in which no outside casing is used.

Like characters of reference indicate corresponding parts in the different views.

15 1 is the base of the instrument. 2 is a reproducer unit or other similar device for transforming electric waves into sound waves. 20 3 is a rod connected to the reproducer unit in the orthodox fashion at one end, and its other end connected to a cone-shaped diaphragm 4 mounted on such rod and held in position by the nuts 5. 25 6 is a second cone-shaped diaphragm mounted on the rod 3 by further nuts 5, and 7 is a third cone-shaped diaphragm mounted on such rod in like fashion. The 30 35 diaphragms 6 and 7 are spaced apart from each other and from the diaphragm 4, said diaphragms preferably being mounted so as to be concentric to each other, and the inclination of the cone surfaces being preferably the same in each. Furthermore, in the forms 40 45 illustrated the diameters of the respective diaphragms vary.

While I have shown the diaphragms in Figs. 1 and 2 enclosed in a casing to simulate the appearance of the ordinary cone loud speaker it is to be understood that they can be mounted in any other type of loud speaker wherein a rod or its equivalent is employed 50 connected to the reproduction unit, and they

can also be used without any casing as depicted in Fig. 3.

By employing a plurality of cone-shaped diaphragms mounted as above described the volume of sound from the instrument can be 55 materially increased without increasing its diameter and improved tone is achieved. It is well known that the diameter of such instruments is limited and consequently their sound volume is limited owing to diaphragms 60 beyond a certain size developing certain undesirable characteristics. No such defects appear in my construction.

From the above description it will be apparent that I have constructed a device which 65 will be compact as well as simple and in which the volume of sound therefrom, as well as the clarity of tone, is materially improved.

What I claim as my invention is:

In a radio loud speaker, the combination 70 with a reproducer unit including a rod, of a plurality of spaced apart cone-shaped diaphragms concentrically mounted on the rod, the inclination of all the cone surfaces of the diaphragms being identical, and the diameters of such diaphragms varying to each other, said diaphragms inserted one within the other.

JOHN BRADLEY DEANE.
